UNITED STATES PATENT OFFICE.

WILLIAM HILLIARD MUNRO, OF SAULT STE. MARIE, ONTARIO, CANADA.

WRENCH.

933,096.

Specification of Letters Patent.

Patented Sept. 7, 1909.

Application filed March 25, 1908. Serial No. 423,226.

To all whom it may concern:

Be it known that I, WILLIAM HILLIARD MUNRO, of the town of Sault Ste. Marie, in the district of Algoma, in the Province of Ontario, Canada, have invented certain new and useful Improvements in Wrenches, of which the following is the specification.

My invention relates to improvements in wrenches, and the object of the invention is 10 to devise a strong and durable wrench adaptable for various uses, which will practically automatically adjust itself to the pipe or nut and when applied will securely grip the pipe and hold the grip as long as it is being 15 worked and until released.

A further object is to make the wrench readily adjustable for different sizes of pipes and nuts etc.

A still further object is to make the 20 wrench of such a form as will effectually prevent its being used beyond the strength of its capacity or size.

The invention consists essentially of a wrench comprising an operating bar or member having serrated teeth at the gripping end thereof and a co-acting bar or member having serrated teeth at the gripping end thereof and forming two jaws and links connecting the jaws, the parts being constructed 30 and arranged as hereinafter more particularly explained.

Figure 1, is a perspective view of my wrench applied to a pipe. Fig. 2, is a side elevation. Fig. 3, is a detail of the supplemental gripping jaw.

In the drawings like letters of reference indicate corresponding parts in each figure.

A is the long bar or member of my improved wrench, which has a rounded end A', 40 serrated teeth A² at the inside, an enlargement A³ intermediate of its length and the major portion thereof tapered as at A⁴ to form a handle.

B is the short bar or member, which is 45 provided with a rounded outer end B' and serrations or teeth B².

C are the upper pair of links, which are connected by the bolts or pins C' and C² to the members A and B respectively. The 50 links C have extra holes C³ for adjustment, so as to bring the members A and B closer together and thereby make narrower jaws.

D are the lower pair of links, which are connected to the members A and B respec-

tively by bolts D' and D². Extra holes D³ 55 are provided in the links D, so as to provide for drawing the members or bars A and B closer together for the purpose aforesaid.

The pair of links C are heavier than the pair of links D on account of the tensile 60 strength being exerted on the links and the compression stress on the links D.

In order to place my wrench in position upon a pipe or nut or the like it is simply necessary to place the pipe between the jaws 65 formed by the bars A and B and press the bars together and hold them temporarily until a turning pressure is exerted on the handle A⁴ when a grip will be immediately established and the pipe or the like may be 70 turned with facility, of course, if the wrench is inverted as shown in the drawing the gravity of the two jaws as they fall together will provide this grip.

I show a supplemental jaw A⁵, which is 75 made of L-shape in cross section and is provided with inner teeth or serrations A⁶ and has a depending portion A⁷, which rests against the shoulder or enlargement A³ of the bar A, so as to take the thrust. A pin or 80 tooth 2 extends through the jaw A⁵ and the bar A, and thereby securely holds it in position. It will now be seen that when the jaw A⁵ is applied, smaller pipes and nuts may be 85 with facility grasped and turned. By providing several of these supplemental jaws with the gripping sides of more or less thickness different sizes of pipes may be gripped with facility. It must be understood, however, that the size of wrench as shown in 90 Fig. 1, will grip more than one size of pipe, it being adapted to grip several sizes, but for very much smaller sizes the supplemental jaw A⁵ may be used.

Such a wrench as I have described is simple and cheap to make, very efficient, very strong and there is nothing liable to get out of order with the same.

The enlargement A³ hereinbefore referred to it will be noticed is partly serrated, so as 100 to aid in the gripping of the article.

What I claim as my invention is:

A wrench comprising a handle member or bar having a gripping inner surface at one end thereof and an enlargement at the rear 105 end of said gripping surface separating said gripping surface from the handle proper said gripping surface and a portion of the

enlargement having teeth thereon, a coacting bar having a gripping surface, links connecting said bars together, a supplemental jaw having teeth thereon and having its inner end engaging with one of the teeth on the enlargement, and a depending side portion on the supplemental jaw engaging with

the side of the handle member and a pin securing said depending portion to the handle member.

WILLIAM HILLIARD MUNRO.
